DESIGN FOR A WRAP-AROUND SKIRT

Emanuel J. Gerli, New York, N. Y.

Application May 25, 1943, Serial No. 110,285

Term of patent 3½ years

To all whom it may concern:

Be it known that I, Emanuel J. Gerli, a citizen of the United States of America, residing in New York city, county of New York, and State of New York, have invented a new, original, and ornamental Design for a Wrap-Around Skirt, of which the following is a specification, reference being had to the accompanying drawing, forming part thereof.

Fig. 1 is a front view of a wrap-around skirt showing my new design.

Fig. 2 is a rear view thereof.

Fig. 3 is a view showing the wrap-around skirt in open position.

I claim:

The ornamental design for a wrap-around skirt, substantially as shown.

EMANUEL J. GERLI.
